UNITED STATES PATENT OFFICE.

ANTHONY BORSELLA, OF NEW YORK, N. Y.

AUTOMATIC CONTROL AND AVIATOR'S COMFORT DEVICE.

1,316,079.

Specification of Letters Patent. Patented Sept. 16, 1919.

Application filed August 8, 1918. Serial No. 248,940.

To all whom it may concern:

Be it known that I, ANTHONY BORSELLA, a citizen of the United States, and a resident of the city of New York, borough of Manhattan, in the county and State of New York, have invented new and Improved Automatic Controls and Aviators' Comfort Devices, of which the following is a full, clear, and exact description.

10 This invention relates to airplanes and has for an object the provision of an improved arrangement forming part of the control which continually tends to cause the airplane to move to a normal horizontal position.

Another object of the invention is to provide an airplane with flat spring members overlapping on each side of the ailerons and their controlling planes positioned in such a manner as to urge the planes back to a neutral position without interfering with the usual control of the airplane.

A still further object of the invention is to provide a resilient steering wheel formed of flat spring members capable of withstanding all of the twisting or back and forth movement while producing a resilient action.

A further object of the invention is to provide foot rests adjacent the steering wheel whereby the foot of the aviator is supported vertically while capable of a free turning movement and constant engagement with the steering bar.

35 In the accompanying drawing:

Figure 1 is a diagram showing the essential parts of an airplane together with an embodiment of the invention.

Fig. 2 is a front elevation of the steering wheel and associate parts as shown in Fig. 1, the same being on an enlarged scale.

Fig. 3 is a section through Fig. 2 on line 3—3.

Fig. 4 is a detail fragmentary sectional view through Fig. 2 on line 4—4.

Fig. 5 is a detail fragmentary sectional view through Fig. 1 on line 5—5.

Fig. 6 is a plan view of a blank disclosing certain features of the invention.

50 Referring to the accompanying drawing by numerals, 1 indicates the lifting planes of an airplane and 2 the elevating planes. These planes are of the usual construction and act in the usual manner. The 55 lifting planes 1 are provided with the usual ailerons 3 which are operated by the usual

mechanism now in common use. A double spring structure is provided for each aileron and an identical spring structure 5 is provided for each of the elevators. These 60 spring structures and associate parts are shown in detail in Fig. 5, wherein it will be seen that the elevator is provided with wearing plates 6 and 7 which accommodate springs 8 and 9, said springs being reinforced by other springs 10 and 11. The various springs 8 to 11 are held in place by rivets 12, or other suitable clamping means so as to normally hold the elevator 2 in alignment with the member 13 to which it is 65 pivotally connected. This construction and arrangement does not materially retard or resist the motion of the elevator when operated by the usual elevating mechanism. The springs 8 to 11 inclusive may be made 70 of any strength and formed flat with outwardly curved ends so as to provide an easy movement of the parts though resisting the pivotal movement of the elevator or ailerons as the case may be, said resistance being in 75 proportion to the strength of the springs. As an instance the springs may be arranged so as to require a twenty five pound pull to move the elevator to a decided angle. As the resistance of the air is usually less 80 than this amount the exertion of the elevator would be comparatively small, and be used only when going up or down, as the springs would automatically return the 85 parts to their proper horizontal position. 90

In addition to using springs for holding the parts in their normal position as just described, the steering post 14 is provided with a wheel 15 having a number of spokes 16 formed of springs shaped somewhat on the 95 order of a Maltese cross. Preferably there are a number of springs forming a spoke 16 as shown in Figs. 2 and 3, though if desired only one spring could be used. This spring is to take up vibration, while at the same time providing ample strength for rotary movement for moving the sprocket wheel 17 and for a back and forth movement for moving the elevator. In addition to providing a resilient action to wheel 15 and thereby making the work of the aviator less tiresome, springs 18 and 19 are rigidly secured at 20 and 21 to the post 14 and to the bracket 22. Auxiliary springs 23 are arranged on each side of each of the springs 18 and 19 so 100 as to normally hold them in a vertical position and to automatically return the post 105 110

14 to a vertical position whenever released by the aviator. By this construction and arrangement the aviator could swing the steering post back and forth as desired for 5 operating the elevator and may release the wheel safely when not desiring to operate the elevator, as the springs will hold the steering post in the proper position, and the spring structure 5 will automatically hold 10 the elevator in a proper position. The springs 4 which are identical with springs 5 hold the ailerons in proper position and consequently will normally prevent rotation of the wheel 15 unless positively moved by 15 the aviator. It will thus be seen that the aviator may release the wheel when in the air and yet move straight forward in a horizontal direction in safety. This is very desirable in battle-planes or any kind of planes used in or near the battle-line, as an injured 20 aviator may turn his machine toward his own lines and then let go of all the parts and the airplane will ordinarily automatically operate until the fuel has been exhausted. 25 In further carrying out the same idea of providing automatic control the rudder 24 is operated by the usual mechanism including the steering bar 25, but said steering bar is resiliently held in a neutral position by 30 the springs 26 and 27 and the auxiliary springs 28 there being one auxiliary spring 28 on each side of each of the springs 26 and 27. These springs extend through the bracket 22 and are secured thereto in any 35 desired manner, as for instance being riveted thereto, while the other springs 26 and 27 loosely fit in U-shaped retaining members 29 and 30. In this way the bar and parts connected therewith are returned to their neutral position when not positively operated. The wires leading to the rudder 24 are connected through a suitable link (not shown) on each end of the bar, and in order to properly reinforce the bar at the ends a 45 fitting 32 is provided as shown in Fig. 2 and in detail in Fig. 6. Each of these fittings are stamped from a blank as shown in Fig. 6 with a rounded portion 33 which acts as a bearing for what may be termed a 50 turntable 34 pivotally mounted on the shoe support 35. From the rounded portion 33 a neck 37 extends into an enlargement 39 and an extension 38. Intermediate the ends of the neck portion 37 extensions 36 and 36' 55 are provided while at the extreme ends of the entire blank extensions 51, 51', 52 and 52' are provided. When the blank is bent upon itself so as to be looped around the end of the bar 25 the extensions 36 and 36' 60 form an encircling fitting as shown in Fig. 2, said extension being connected by a suitable rivet 53 to which a link (not shown) is connected if desired and the rudder wires connected to said link. The extensions 38 and 38' are bent forming a substantially U-shaped retaining member 29 and 39 as shown in Fig. 4 so that spring 27 may properly be connected at its free end with the outer end of the bar 25. The end extensions 51 and 51' and 52 and 52' are 70 bent around for forming an inner clip 54 which encircles bar 25 whereby the entire fitting is clamped to the bar without the use of rivets or other securing means. If desired, of course, one or more screws may be 75 provided to insure against any accidental slipping though the screws ordinarily are not necessary. When the fitting is properly placed in position an arm 39 is provided with an aperture 41 and acts as a brace 80 or bracket for the rod 40. It will be evident that there is a fitting or stamping at each end of the bar as shown in Fig. 6, and also there is provided a shoe support 35 at each end of the bar. As shown in Figs. 2 and 4 85 the shoe support 35 is provided with a heel portion 45 having a raised end 46 against which the heel rests when the foot is not in operation whereby the aviator may have his feet in proper place on the bar 25 but resting against a support from beneath. The shoe support 35 is hinged or pivotally mounted on the turntable 34 which rotates on its supporting pin 47 whereby the support has universal movement. However, 90 the support is normally held at an angle as shown in Fig. 4 by means of the springs 48 and 49, which springs surround the rod 40. Spring 49 acts on the end 50 of rod 40 and on the stop or bracket 39, while spring 100 48 acts in the opposite direction, namely on the stop or bracket 39 and on the shoe support 35 whereby when one end is swung to a different position the springs will act to bring it back. This provision of means 105 for supporting a shoe while allowing a continuous contact with the bar 25 will permit the aviator to rest his feet and legs when not positively operating the rudder. The arrangement of the springs 18 and 19 and 110 associate parts will allow the aviator to rest his arms when traveling in a straight horizontal course. It will thus be seen that the structure just described has double advantages, namely to permit the aviator to 115 rest himself and to permit a wounded aviator to turn his machine toward his own lines in case of a battle and then allow the machine to fly without controlling it. 120 In connection with the movement of the airplane in the air it is of course known that the controls of an ordinary airplane are arranged in such a way that the movement of the pilot rapidly becomes complex, in order to answer the different requirements 125 exacted by the condition of the air as the airplane moves along. The movement of the aviator in controlling his airplane may be slow or fast in proportion to the intended effect, though ordinarily his action is not 130

in any exact proportion so that it requires several opposite movements before the airplane can be brought to the desired position, or back to the position from which it has been forced by some air currents. The continuous movement back and forth of the joy stick or the control wheel is fatiguing, as the aviator to keep a proper course must continually move this slightly to counteract the action of the different air currents on the ailerons, elevator and the rudder. The extra movements of the controlling device by the aviator is caused by him not perceiving at the start the phenomenon to be corrected. For instance, in case an air current gives the airplane a tendency to take a nose dive the inclination of the airplane must be sufficiently pronounced for the pilot to notice it and in moving the airplane back it is usually the case that the same is brought back too far so that a back and forth movement of the controls are necessary. Moreover a slight movement in any direction of the joy stick or of the control wheel causes such a wide variation in movement that it is impossible for an aviator to manually exactly proportion his efforts.

It is necessary for an aviator to continually have at least one hand on the control when in the air and if possible both hands so that in long flights reliefs must be provided, or the aviator must withstand severe strains continually. To obviate this continuous strain on the aviator the various controlling springs and associate parts are provided which act in at least two important ways, namely; to conserve and save the strength of the pilot and second to start the reaction in the right direction as soon as a disturbing action begins, as for instance when a gust of wind or an air current gives the elevator a movement which will have a tendency to produce a nose dive. The springs on the elevator and the controlling bar will resist such movement and return the elevator to its correct position as soon as possible. In addition in case the movement is considerable the aviator will feel the pull immediately and may act accordingly which is not the case without the use of these springs, as the aviator only knows that the machine is diving when he observes the earth or some other object, which is impossible when passing through a cloud. In this way the motion of the machine is counterbalanced from the moment of their inception of the disturbing action, namely the air current and usually can be entirely suppressed automatically by the springs. This feature of automatically returning the airplane to its proper position and automatically resisting any change therefrom without effecting the control of the aviator is extremely useful in long distance flights,

night flights, in fog and also in clouds, and also in fighting machines, as it provides a horizontal plane in which the aviator may rest while using both his hands on the gun if he so desires. Another result of the action of these springs is that the aviator will have an opportunity to make repairs on the gun in case it jams without danger of immediate collapse or diving of his airplane.

In using the springs in fighting machines they are of extreme importance in case a bullet cuts one of the wires to the elevator, rudder, or in fact any of the controlling device, as said controlling device will be out of control by the aviator, but will be held in control by the springs and will have a tendency to hold the airplane in a horizontal position. In case the wires of the elevating planes were severed the machine would fly a substantially straight horizontal course and could be easily brought to the ground by the aviator by slowing down or stopping the motor. This brings in and utilizes the forces common to all airplanes, namely the three forces which may be classified as follows: 1st, The resultant of the forces exerted by the air upon the whole machine; 2nd, the pull or push of the propeller; 3rd, the weight of the airplane. As is well known all of the modern airplanes are built so that these three forces meet approximately one foot below the center of gravity and in view of this fact if the engine is slowed down or stopped either intentionally or accidentally the airplane will gradually volplane to the earth and if under some control may land safely without injury. This landing of the airplane with or without injury is of importance where it is desired to save the secrets of the airplane or save the wounded aviator. If the aviator is mortally wounded, but is sufficiently conscious for a few seconds after being wounded he may turn his machine toward his own lines and let the control go. In case he should die the machine would fly substantially in a straight horizontal course until out of fuel and then descend in the same manner as if the engine was slowed down or stopped intentionally.

What I claim is:

1. The combination with an airplane provided with a steering bar connected with a rudder of a plurality of spring members rigidly secured to the stationary part of the airplane and slidingly connected with the ends of said bar for resiliently holding the bar in a given position and the rudder in a neutral position.

2. The combination of an airplane provided with a rudder and a steering bar therefore of a pair of flat springs rigidly secured at their centers to a stationary part of the airplane, a reinforcing spring for each of the first mentioned springs, and means ex-

tending from said steering bar on each side of the respective ends of the first mentioned springs whereby the bar is resiliently held in a neutral position and automatically returned to said position when moved therefrom.

3. The combination with an airplane with a pivotally mounted steering post of means for resiliently holding the steering post in a given position and returning same to said position when moved therefrom when released, said means comprising a pair of comparatively short flat spring members on each side of said post, a single spring member arranged on each of the flat spring members, said single spring members being longer than the short spring members and connected at one end to the post, and means connecting the opposite ends of said last mentioned spring members and the first mentioned spring members to a stationary part of the airplane.

4. The combination with an airplane provided with a controlling post of a steering wheel for said post formed with resilient spokes capable of flexing substantially in line with the axis of the wheel.

5. The combination with an airplane provided with a controlling post of an aileron controlling wheel for said post formed with a plurality of resilient spokes, said spokes being formed from a flat sheet metal each of which being cut to produce a central section and a plurality of radiating spoke structures, said spokes being superimposed with the longest spoke structure extending to the rim of the wheel, said resilient spokes being positioned to flex substantially parallel with the axis of the wheel.

6. The combination with an airplane provided with a rudder and a steering bar therefore of shoe supporting members universally positioned adjacent each end of said bar.

7. The combination with an airplane provided with a rudder and a steering bar therefore of a fitting at each end of the bar formed to extend around the end of the bar and partially on each edge thereof with a brace on one edge and a turntable support on the opposite end, a shoe supporting member formed with a turntable rotatably mounted on the turntable support, and a pivotal pin for connecting said turntable and the turntable support.

8. The combination with an airplane provided with a rudder, a steering bar therefore of a shoe support pivotally connected to said bar near each end thereof, and a pair of opposing springs arranged at the front of the shoe support for resiliently holding the shoe support in a given position.

9. The combination with an airplane provided with a rudder and a steering bar therefore of a shoe support universally joined to said bar near each end thereof, said shoe support being formed with an outwardly extending member against which the heels of an aviator are adapted to rest, a rod pivotally connected with each of the shoe supports at the front thereof, a bracket adjacent each end of said bar formed with openings through which said rods extend, and a spring surrounding said rod on each side of said bracket for resiliently resisting movement in either of two directions so as to resiliently hold the shoe support at substantially a predetermined angle.

ANTHONY BORSELLA.
